Attorney.

UNITED STATES PATENT OFFICE.

FREDERICK WAMBACK, OF GREENWICH, CONNECTICUT.

BOTTLE-RACK.

1,287,151.

Specification of Letters Patent. Patented Dec. 10, 1918.

Application filed February 25, 1918. Serial No. 219,045.

To all whom it may concern:

Be it known that I, FREDERICK WAMBACK, a citizen of the United States, residing at Greenwich, in the county of Fairfield and 5 State of Connecticut, have invented certain new and useful Improvements in Bottle-Racks, of which the following is a specification.

My invention relates to a rack or container and particularly to such an article as 10 may serve for the deposit of bottles containing milk and for the collection of such bottles when empty.

One important object is to provide a 15 structure of this type optionally having one or more compartments, but having preferably a plurality of compartments differing in size and being effectively correlated and braced.

Another object of importance is to provide a structure of this class which may be 20 made from strip metal and have its parts effectively constructed and braced in the particular manner hereinafter described, 25 relative to accompanying drawings illustrating my present preferred embodiment.

In the drawings referred to:—

Figure 1 is a perspective view of the improved rack and fragment of a post to 30 which it is secured;

Fig. 2 is a view in front elevation;

Fig. 3 is a view in side elevation looking 35 toward the left of Fig. 1;

Fig. 4 is a detail cross-sectional view on the line 4—4 of Fig. 2, and

Fig. 5 is a detail cross-sectional view on the line 5—5 of Fig. 2.

Referring specifically to the drawings, I first provide, preferably from a bar or strip 40 of metal, a fastening bar 6, which is bent at the upper extremity and returned downwardly to provide a side arm 7. This side arm 7 extends about half way of the length of the fastening bar 6, and it then bends 45 horizontally to provide a bridge 8. From bridge 8, the bar is bent upwardly to provide another side arm 9. A strut 10 is bent upwardly and outwardly from the lower extremity of attaching bar 6, so as to be 50 disposed at an angle, and this strut terminates in a tang 11 which supports the bridge 8. A rivet 12 may secure the tang 11 and bridge 8 together. One or more rivets 13 may secure the bars 6 and 7 together. 55

A ring or frame 14 is provided which

preferably has a laterally projecting reinforcing bead or flange 15 at its upper edge. This ring or frame is preferably formed from a single strip which at one extremity 60 overlaps the other extremity, and is secured thereto by one or more rivets or other fastening means at 17. Arm 7 rests against the exterior of frame 14 beneath the bead 15, and a rivet or other fastening means 18 65 may pass through the bar 6, arm 7, and frame 14, to rigidly secure these three parts together. Side arm 9 is disposed in intimate contact with the end of portion 16 so as to be braced thereby against lateral movement 70 in one direction. A rivet or other fastening means 19 may pass through the arm 9 and frame 14, to rigidly secure these parts together.

Secured to the bridge 8, as by means of a 75 rivet or other fastening means 20, is a base bar 21 which is bent upwardly to form a side bar 22 and is bent downwardly to form another side bar 23, then horizontally to form a base bar 24 and then vertically to 80 form a further side bar 25. Side arm 25 is riveted or otherwise rigidly secured as to 27 to a ring or frame 26, preferably smaller in size than frame 14.

Like ring 14, ring 26 is preferably made 85 in one piece, having a portion at 28 overlapping the other extremity of the ring, and also having a reinforcing and laterally projecting bead 29. It will be noted that the frames 14 and 26 are fastened in alinement. 90 Accordingly the space below and between the bead should be filled. To this end, portion 28 and the side arms 22 and 23 extend into that space, and a rivet or other fastening means 30 passes through the frames 14 95 and 26, and the side arms 22 and 23. A rivet 30^a may fasten arms 22 and 23 together.

Suitable alined openings 31 are provided in the fastening arm 6 and side arm 7, and alined openings are also provided at 32 in 100 the strut 10 and arm 6. Suitable fastening screws or nails 33 may pass through the openings and into a support, such as the post 34 suggested in Fig. 1, it being understood of course that the article may be secured in any suitable position and to any desired object.

It will be realized that the article provides a first rack consisting of the frame 14, side bars 7, 9, and 22 and base bars 8 and 21. A milk bottle or other object may be disposed in this rack for deposit or collec- 110

tion. The frame 26, side arms 23 and 25 and base bar 24, provide a second rack for the deposit or collection of articles like milk bottles. This rack however, is preferably smaller in size than the other rack, and the bar 24 is higher than the bar 21 so that the smaller rack may better be braced from the larger rack.

It is to be noted that fastening bar 6, 10 side arm 7, base bar 8, side arm 9, strut 10 and tang 11, are all made in a single piece while base bar 21, side arms 22, 23 and 25 and base bar 24 are made in a single piece.

As I have shown merely my present preferred embodiment, it is to be understood that I reserve the right to make such changes as fall within the spirit and scope of the invention as defined by appended claims.

I claim:—

20 1. In an article of the class described, a rack having a side and a base, an attaching bar opposite the side and depending from and below the rack, fastening means common to both the side and the attaching bar, 25 and a strut intermediate the base and the bar.

2. In an article of the class described, a rack, sides therefor, a bridge joining said sides, one of said sides being returned and 30 extending below the bridge, and an upwardly and outwardly extending strut intermediate the returned portion and said bridge.

3. In an article of the class described, a 35 rack having sides and a bridge joining the sides and extending across the bottom of the rack, a second rack, and a bar structure extending at an angle to and laterally from the bridge across and beyond the bottom of the first-mentioned rack to both serve as a 40 base for the first-mentioned rack and as a support for the second-mentioned rack.

4. In an article of the class described, a 45 rack, a bar having sides for the rack and a bridge joining the sides, one of the sides being returned and extending below the bridge, an upwardly and outwardly extending strut joining the returned portion and said bridge, a second rack, said second rack having sides 50 and a base, said base being disposed above the bridge, and means extending from one of the last mentioned sides connected to the bridge and extending at substantially a right angle thereto.

55 5. In a device of the class described, a rack, a bar having sides for the rack and a bridge joining the sides, one of the sides being returned and formed into a fastening bar, said fastening bar extending below the bridge, and at its lower end being bent upwardly and outwardly into a strut, and said strut supporting said bridge.

6. In a device of the class described, a 60 rack, said rack having a downwardly extending arm and a base, a second rack, said

second rack provided with a downwardly extending arm contiguous with the first arm, and a brace means for the arms extending below the base to resist vertical and lateral strains.

7. In a device of the class described, a plurality of racks having frames, one of said frames having an outwardly projecting portion engaging the other frame and providing a space beneath it between the frames, 75 side bars for the rack disposed in said space, one of said racks having a portion overlapping the remainder and disposed in said space, and means extending through said frames and side arms rigidly securing them 80 together.

8. In a device of the class described, a rack having a frame provided with an overlapped portion, a side fastened to the frame and abutting the end of said portion to 85 brace the side against strain from one direction, means extending from the side forming a base for the rack, fastening means associated with the base, and brace means associated with the base and fastening means.

9. In a device of the class described, a plurality of frames, fastening means extending downwardly from one of the frames, side arms for one of the frames, a bridge intermediate said side arms and fastening 95 means, a strut rising from the fastening means and engaging the bridge, a base member extending at substantially a right angle to the bridge, a side arm rising from the base member, a side arm contiguous with the 100 third mentioned side arm, means to secure the third and fourth mentioned side arms and frames together, a base member extending from the fourth mentioned side arm disposed above the first base member, and a 105 side arm rising from the second base member and secured to one of the frames.

10. In a device of the class described, a plurality of frames, one of the frames having a laterally projecting portion engaging 110 the other frames and providing a space beneath the portion between the frames, one of the frames having an overlapping portion disposed in said space, a bar having contiguous side arms disposed in said space, fastening means extending through the frames and said side arms, a base bar extending from one of the side arms, a base bar higher than the first base bar extending from the other side arm, a third side arm extending from the second base bar, means to 115 secure the third side arm to one of the frames, a fourth side arm secured to the other frame, a bridge extending from the last mentioned side arm, a first base bar being secured to said bridge and disposed at substantially a right angle thereto, a side arm rising from the bridge and being returned into a fastening bar extending below the bridge, an upwardly and outwardly ex-

tending strut rising from the fastening bar and supporting the bridge, and fastening means to extend through the last mentioned side arm, fastening bar and strut.

- 5 11. In a device of the class described, a rack having a frame provided with an overlapped portion, a base for the rack, a side rising from the base and abutting the end of said portion to brace the side against strain
10 in one direction, and means to fasten the side in rigid relation with the frame.
12. In a device of the class described,

racks having outwardly projecting reinforcing means providing a space between the racks when aligned and the reinforcing means 15 are contiguous, bases for the racks, a side arm for each rack, and said side arms being contiguous and extending into said space.

In testimony whereof I have affixed my signature in the presence of two witnesses. 20

FREDERICK WAMBACK.
